UNITED STATES PATENT OFFICE.

EUGENE E. ARNOLD, OF LYNCHBURG, VIRGINIA.

SIGN.

Application filed May 29, 1926. Serial No. 112,543.

This invention relates to signs and more particularly to a frame adapted to be secured upon a post or other suitable support and carry a display card.

5 One object of the invention is to provide a frame in which a card may be mounted and directions or advertising matter upon the card prominently displayed.

Another object of the invention is to so 10 construct the frame that the display card may be readily inserted or removed and securely held in place when mounted in the frame.

This invention is illustrated in the accompanying drawings, wherein

15 Figure 1 is a perspective view of the improved frame;

Fig. 2 is a transverse sectional view through the frame taken on the line 2—2 20 of Fig. 1;

Fig. 3 is a longitudinal sectional view through the frame.

The frame forming the subject-matter of this invention is primarily intended for use 25 in connection with a post or standard 1 and, therefore, has its lower longitudinally extending bar 2 provided with a depending socket 3 of such diameter that it may fit snugly upon the upper end of the standard. A

30 set screw 4 passes through a threaded opening formed in the socket to engage the standard and firmly but releasably secure the socket. Arms 5 extend in opposite directions from the socket and are disposed longitudinally

35 of the frame with their outer ends joined to the lower bar 2. These arms serve to brace the frame and prevent it from being readily broken loose from the socket. The upper bar 6 of the frame is joined to the lower bar

40 by end bars 7 and 8, and from an inspection of Fig. 3 it will be seen that the end bar 7 and upper and lower bars are formed along their inner edge portions with communicating grooves 9, 10 and 11 to receive marginal portions of a sign 12. The sign or

45 display card 12 is passed into the frame through a slot 13 formed longitudinally in

the end bar 8 and is adapted to be retained in place by a pin or cotter key 14 passed through aligned openings 15 formed in the 50 ears 16 which project from the end bar 8 intermediate its upper and lower ends. A beading or border 17 extends around the frame and serves not only to reinforce the frame and prevent it from being weakened 55 by the grooves and slot but also to ornament the frame and give it an attractive appearance. By having the frame formed as shown in the drawing and set forth above, a display card or sign having appropriate 60 instructions of advertising matter provided thereon may be prominently displayed. It should be further noted that the sign or card will be securely held in place but may be readily removed and a new one substituted. 65

Having thus described the invention, I claim:

A frame of the character described comprising end bars and upper and lower bars joining said end bars, enlargements being 70 provided at the corners of the frame, beads extending longitudinally along the outer edge faces of the bars and rigid with the bars and enlargements, one end bar and said upper and lower bars being formed with 75 communicating grooves opening through their inner faces, the other end bar being provided with a longitudinally extending slot opening through its bead and inner edge face and communicating with the grooves of 80 the upper and lower bars, the slotted end bar being provided with ears intermediate its ends separated by the slot and formed with aligned openings to receive a fastener for retaining a card in the frame with marginal portions of the card seated in the 85 grooves and slot, a socket member rigid with and depending from the lower bar intermediate its length, and arms having their ends rigid with the bead of the lower bar 90 and said socket member.

In testimony whereof I affix my signature.

EUGENE E. ARNOLD. [L. S.]
